UTILIZATION OF THE PERCEPTIBLE HEAT OF FINISHED COKE

Filed Feb. 24, 1926

UNITED STATES PATENT OFFICE

JOSEF SCHAEFER, OF DORTMUND, GERMANY

UTILIZATION OF THE PERCEPTIBLE HEAT OF FINISHED COKE

Application filed February 24, 1926, Serial No. 90,419, and in Germany April 15, 1925.

This invention has reference to means of utilizing the perceptible and sensible heat of the finished coke freshly delivered from the coking ovens, retorts or the like, and it is intended to utilize this heat in a highly economical manner as an element both in the heating of the coke ovens as well as for other purposes, and in view thereof it is one of the important objects of the invention to increase the heating value of this great amount of caloric units present in the finished coke and of the combustible gases of high heating value retained therein by utilizing them in the dry cooling of the coke by means of so-called indifferent or rather inert neutral uninflammable gases and by so conducting this procedure that the heating capacity of the perceptible heat is utilized and increased in such a manner as to produce additional heating gases by decomposition or chemical reaction. In the procedure of cooling the hot finished coke by means of so-called inert or neutral gases rich in carbon-dioxide which are caused to circulate through the coke and through any suitable means for the utilization of the heat referred to a partial conversion of the carbon-dioxide contained in the inert or neutral gases into carbon monoxide is effected in the hot portions of the mass of coke, and this carbon monoxide is transformed back again in part into carbon-dioxide upon the cooled gases reentering the cooled portion of the supply of coke to be cooled and in this operation the carbon is separated out from the carbon monoxide in pulverulent or dust-like condition in accordance with the formula $2CO = CO_2 + C$. The carbon-dioxide in the course of circulation of the cooling gases through the coke is then partly reconverted into carbon monoxide and so in succession, so that in the process of circulation referred to carbon is continuously precipitated in pulverulent or dust-like condition. With a view of overcoming this difficulty and of attaining other important objects and advantages provision is made in accordance with this invention to mix and burn the cooling gases referred to with air of combustion before introducing them into the various devices which may be used for the utilization of their heat and after having passed them through the coke cooling chambers in which they have taken up a certain amount of combustible gases, both as a result of their becoming mixed with the carbon monoxide above referred to and of the absorption of the gases still contained or retained in the coke and furthermore than that in consequence of any possible subsequent coking of unfinished pieces of coke. By this means the gases referred to will undergo a combustion causing the carbon monoxide contained in them to be converted into carbon-dioxide, so that the gases may be made to reenter the coke-cooling chambers free from carbon monoxide and thereby to avoid the precipitation of carbon in the cooling chamber. Moreover, by working in this manner, not only the sensible heat, but in addition thereto the heat of combustion of the combustible gases which have been taken up by the inert or neutral gases will be utilized in the apparatus or heat-utilizing means. Particularly favorable results may be obtained by carrying on the combustion of the gases referred to in a special compartment before passing them through the heat-utilizing means or, by means of preheated air of combustion, in such heat-utilizing means itself or before passing therethrough, in view of the fact that, on account of the cooling action of the cold parts to be heated in the heat-utilizing means upon the flame, the combustion in such heat-utilizing means itself cannot be carried through at all, or at least not satisfactorily without correspondingly preheated air of combustion. In the treatment of the glowing hot pieces of coke with the cooling gases steam, as has already been suggested heretofore for the cooling of newly made coke, or water may be added, which addition is also instrumental in counteracting the separation and precipitation of carbon in the cooling chambers and in assisting the desulphurizing of the coke. In this connection it is a further object of my invention to produce and to assist the circulation and the revolving of the gases by the addition of steam, such steam or water vapors being for instance introduced by an injector or by equivalent means.

In accordance with another feature of my invention the employment of the inert or neutral gases referred to for cooling purposes, both without as well as in the presence of 5 steam or water vapors, may extend to part of the mass of the freshly discharged coke only, and by this means additional important advantages will be realized, particularly in the case of coke ovens which are heated with 10 the so-called lean or poor gases, that is to say, gases comparatively low in heating value, such as producer gas or blast furnace gases, for instance. In the case of coke ovens heated by the gases referred to and which herein- 15 after will be designated broadly as lean or poor gases there is the difficulty that, in case the glowing hot coke in the coke-cooling chambers is employed for preheating only said lean gases, but not for preheating the air 20 of combustion, large amounts of waste heat will result for which, as heretofore practised, it is frequently not possible to provide sufficient means of utilization. On the other hand, however, if the air of combustion 25 would also be preheated in these ovens, the amount of heating gas would be relatively reduced in such cases and they would not suffice for the complete absorption of the heat of the glowing mass of coke. Now, in order to 30 overcome this difficulty in the successful utilization of the perceptible and sensible heat and of the cooling of the freshly prepared coke in the case of ovens heated with lean or poor gases, the perceptible and sensible 35 heat of the coke in this case is more intensely utilized in accordance with my invention by making use of neutral gases for withdrawing the sensible heat of only part of the newly made and freshly discharged finished coke 40 and in this operation water vapors, steam or water, if so desired, may be admitted to these gases before their admission to the cooling chamber. Another portion of the hot quantity of coke is employed for the preheating 45 of said lean or poor gases, while the air of combustion is preheated on the regenerative or recuperative principles. In further pursuance of this feature of my invention the heating gases which have thus been heated 50 by the newly made coke may have their heat further considerably increased by suitable heat-exchanging means. When working in this manner, the raising of the temperature of the heating gases to the degrees of 55 heat commonly employed in regenerative and recuperating furnaces in combination with the preceding increase of the heating value of the gases resulting from their passage through the glowing pieces of coke will result 60 in a reduction in the consumption of gas as compared with the preheating of the heating gas by means of the glowing coke exclusively, or as compared with the preheating of the gas by regenerative and recuperating means 65 exclusively. The neutral gases obtained, be-

fore parting with their heat, may, moreover, be mixed with a portion of the gases of combustion or smoke gases produced in the oven and particularly with the smoke gases directly discharged therefrom or with smoke gases 70 which have passed through the gas-preheating means. The mixing of the smoke gases discharged from the oven with the neutral gases heated by the coke presents the advantage of an increase of the heating value of 75 this mixture in consequence of the excess of air contained in the smoke gases escaping from the oven. These and other objects and advantages 80 of my invention may find expression in different embodiments and will be further described with reference to the accompanying drawing showing various forms of exemplification thereof which have been found suitable for the purposes of the invention. In 85 the drawing Fig. 1 illustrates diagrammatically and in plan view a coking plant embodying the principles of this invention. Fig. 2 is likewise a vertical elevational view of the plan referred to seen at right angle to Fig. 1 90 and Fig. 3 illustrates diagrammatically a modification of the plant for the carrying out of the process, particularly in connection with ovens heated with the lean or weak gases referred to. 95

The coke ovens indicated particularly at *c* in Figs. 1 and 2 are provided in the well known manner with the cooling chambers *k* for the coke, which may be disposed underneath the ovens or at an inclination in front 100 thereof, as indicated in Fig. 2 of the drawing and into which the finished glowing pieces of coke are discharged from the ovens. Into these coke cooling chambers *k* neutral gases as above referred to, including, for instance, 105 smoking gases, are introduced from below by a distributing channel *a* and preferably by means of a steam injector *s*. The gases heated by the coke are withdrawn from the top of the chambers *k* and are conducted, as indicated by the arrows, into the collecting channel *b* and are then introduced into one or a plurality of combustion chambers *v* (Fig. 1) 110 in which they are mixed with air of combustion, for instance, by means of a grate or the like in very fine distribution. As the air of combustion I may employ, for instance, the hot air withdrawn from the air heaters of the coke ovens or preheated by waste heat in any other manner, so that in the combustion chambers the temperature required for the combustion may be sure to be obtained. From the combustion chambers *v* the gases pass to the station or device for the utilization 115 of the heat, which may, for instance, comprise a steam boiler heated by waste heat and adapted to produce the cooling of the gases; thereupon the gases are again conducted by the channel *a* to the several cooling chambers *k* for the coke which 120 125 130

happen to be charged from the ovens. The excess of gases resulting from the admission of steam and the taking up of gaseous constituents from the coke may be withdrawn 5 at the rear of the heat-utilizing means or station *w* and may be led into the chimney *f*, and whenever necessary or desired, may be submitted to any further treatment of utilization of valuable constituents. In view of the 10 fact that the gases leave the heat-utilizing means or station *w* with a temperature which is mostly above the boiling point of water, they may be mixed with water which is vaporized thereby, instead of mixing them with 15 steam.

The gases are cooled down considerably by their utilization in the heat-utilizing means or station *w*, and a further cooling is effected by the introduction of steam from the injector *s*, so that their temperature may, for instance, be as low as, say about 150° C. upon entering the coke cooling chambers *k* from which they escape at a temperature of for instance approximately 750° C. A further increase of temperature is produced by the combustion at *v* and the entire amount of carbon monoxide is thereby converted into carbon-dioxid.

In case it is desired to obtain water gas in the cooling chambers *k* a special steam conduit *d* may be provided in the exemplification under consideration, this conduit being connected with the bottom part of the several cooling chambers *k* which, in this case, are provided at their top portion with a special collecting conduit *e* for the carrying off of the water gas produced. In this case the chambers *k* which happen to be freshly charged with hot-finished coke are first fed 40 with steam and after the coke has become sufficiently cooled down, the connections are changed, so as to put the chamber in communication with the channels *a* and *b*.

By working in this manner from about 3 45 to 4 percent by volume of water gas in the total amount of the circulating gases may be obtained.

In the modification shown by way of example and diagrammatically in Fig. 3 of the drawing and which is particularly of advantage in connection with coke ovens heated with lean or poor gases, as above referred to, the cooling chambers for the coke are subdivided into a section *k*¹ and a section *k*². Through this section *k*¹ and a heat utilizing station or device *w* neutral gases are caused to circulate as above described to which may be added steam at *s* in the manner set forth 60 with reference to the other exemplification, thus, for instance, by means of a steam injector for effecting the circulation. Instead of steam water may be added which is vaporized by the gases and the excess of gases produced 65 may be discharged through the chimney *f*,

as set forth with reference to the other exemplification.

Into the other section *k*² of the coke-cooling chambers and likewise charged with glowing hot coke, lean or poor gas employed for the heating of the coke oven, such as, for instance, producer gas or blast furnace gases may be introduced by way of a conduit *h*. The heating value of the gases is thereby increased by the partial conversion of the 75 carbon dioxid contained therein into carbon monoxid and by the partial transformation of the water contained in the gases to water gas as well as by the taking up of the gaseous constituents still remaining in the coke, and the coke is, moreover, desulphurized to a large extent. The thus preheated heating gases are then introduced into one of the gas heaters, the heater *g*¹, for instance, such heaters being constructed on the regenerative or recuperative principle or the like and comprising one or two or several compartments in which said heating gases are further heated to a still higher temperature and they are then burned in the heating flues of the ovens *c*, together with the air of combustion which has been preheated in the air heaters *l*¹, likewise comprising one or two or more compartments. The smoke carrying gases resulting 85 from the combustion are divided, one part passing through the air heaters, regenerators or recuperators *l*² of the other side of the battery of ovens and, after having been cooled down therein very low, are discharged through the chimney *f*, while another portion of the said smoke carrying gases or gases of combustion passes through the gas heater *g*² or gas regenerators that are to be employed in a succeeding stage and escape therefrom with a still comparatively high temperature, inasmuch as the preheated heating gases upon the reversal of the damper for the change of direction of the gases are made to pass through the gas generators *g*² with a 90 rather high temperature. This portion of the smoke carrying gases or gases of combustion which are discharged at *m* from the section *g*² of the oven and which do not pass through the hot coke in the section *k*² are 95 mixed in the exemplification of Fig. 3 with the neutral gases circulated through the section *k*¹ and discharged therefrom in the heated condition, before the gases are passed into the heat-utilizing device or station *w*. The 100 combustible gas constituents which have been taken up by these gases from the coke will then be burned by the excess of air which is always present in the smoke carrying gases from the ovens and the heat liberated thereby becomes available in the heat-utilizing 105 means or station *w* in form of an increase of efficiency thereof. Part of the exhausted gases, smoke gases or gases of combustion 110 discharged from the utilizing means *w* may then be reintroduced into the coke-cooling 115 120 125 130 135

chambers k^1 in the quantity required thereby and re-circulated therein, and inasmuch as in the reversal of the draft the gases from the section k^1 with the smoke carrying gases the 5 sulphur which has been taken up from the coke is likewise burned, the gases which re-enter the section of chambers k^1 behind the stationary device w are again adapted for the reception of new quantities of sulphur. The 10 remaining part of the gases discharged from the device w escapes from the chimney f . Means not shown herein may be provided for the utilization of the burnt sulphur contained in the gases or of other valuable constituents 15 thereof. Upon the reversal of the draft and of the direction of the gases, the smoke carrying gases heated in the section k^2 are introduced into the regenerator g^2 , causing at the same time the heating of the air of combustion 20 in the device h , while the cooled smoke carrying gases from the heat-regenerator h^1 for the air are introduced into the chimney and the smoke carrying gases from the regenerator g^1 are mixed with the gases coming 25 from the section k^1 . The corresponding direction of the draft is indicated in Fig. 3 by arrows in parentheses. The mixture of the gases escaping from the gas regenerators g^2 or g^1 with the gases discharged from the 30 section k^1 and the combustion of the combustible constituents contained therein, instead of being effected, as shown in Fig. 3, in the conduit through which they are made to pass, may also take place in a special combustion chamber, as shown in the procedure and form of construction according to Fig. 1 and before reaching the heat-utilizing means, and in this case the same as in the procedure according to Fig. 1 water gas may be produced 40 by the admission of steam alone into the chambers k^1 and k^2 before allowing the cooling gases to enter said chambers.

The different temperature conditions in the modification of the invention as particularly shown in Fig. 3 in a general way may be as follows:—From the cooling chambers k^2 the heating gases are introduced at about 45 750° into the regenerators g^1 or respectively g^2 from which they escape at an increased 50 temperature into the heating flues of the ovens, while the smoke carrying gases passing out from the other gas regenerator g^2 (or respectively g^1), though likewise increased in their temperature, have a temperature 55 somewhat below the heating gases from the other gas regenerator. After having been mixed with the neutral gases from the section k^1 which escape at a temperature of about 750° C. the mixture of the gases shows 60 a temperature somewhat around 800° C. which is, however, further increased by the 65 then ensuing combustion of the combustible constituents thereof, so that the gases will enter at this increased temperature into the 70 heat-utilizing device w from which they es-

cape at a temperature as low as about 200° C. On the other hand, the gases from the 75 air regenerator h^1 may enter the chimney f may enter the chimney with a temperature of about 300° . In view of the reduction of the carbon dioxid to carbon monoxid which occurs in the cooling chambers k^2 and in consequence of the taking up of volatile constituents blast furnace gas which may, for instance, be employed in these chambers is increased in its heating value from about 1000 thermal units/cube meter to about 1250 metric thermal units/cube meter equivalent respectively to 3.96 B. t. u. and 4.96 B. t. u. per cubic foot of gas. 80

The invention has been shown and described herein in its broad aspects only, and it is obvious and should be understood that it is not restricted to the particular arrangement and construction of parts shown in the drawings and referred to in the specification merely by way of exemplification, but these and other features of the invention may be modified and altered in accordance with varying conditions of application and without thereby deviating from the spirit and scope of the invention, as fully set forth in the appended claims. 85

I claim:—

1. The process of treating fresh incandescent coke to recover the heat values thereof, which comprises dividing the supply of such coke into two portions, treating one portion by passing therupon lean gases of low thermal value, passing gases rich in carbon-dioxid and of lower temperature than the coke into direct heat exchanging contact with the other portion, and mixing the gases, then leaving the two portions with each other. 90
2. The process of treating fresh incandescent coke to recover the heat values thereof, which comprises dividing the supply of such coke into two portions, passing lean gases of low thermal value and of lower temperature than the coke into direct heat exchanging contact with one of said portions, passing carbonaceous heating gases, containing much carbon-dioxid into direct heat exchanging contact with the other portion of the coke, uniting the gaseous products leaving said portions after the treatment, and burning the then resulting gas mixture out of contact with the coke, and abstracting the heat from the burning gas mixture. 95
3. The process of treating fresh incandescent coke to recover the heat values thereof, which comprises dividing the supply of coke into separate portions, passing different kinds of carbonaceous heating gases of lower temperatures than the coke, and of which each kind contains different amounts of carbon dioxide and possesses different degrees of low thermal values into direct heat exchanging contact with the respective coke. 100

portions, mixing air with part of the gaseous products obtained thereby, burning the mixture, and preheating the heating gases by heat exchange with the products of combustion 5 obtained.

4. The process of treating fresh incandescent coke to recover the heat values thereof, which comprises dividing the supply of coke into separate portions, passing different 10 kinds of carbonaceous heating gases, each possessing different degrees of thermal values and carrying different amounts of carbon-dioxide into direct heat-exchanging contact with the respective coke portions, raising the 15 heat of certain portions of the then resulting gaseous products, and mixing them with air, burning the air-mixture abstracting the heat from the burning mixture and causing air and certain of the carbon-containing heating 20 gases to pass in heat-exchanging relation with the products of combustion.

5. The process of treating fresh incandescent coke to recover the heat-values thereof, which comprises dividing the supply of 25 coke into two portions, passing lean fuel gases of low thermal value into direct heat-exchanging contact with one portion and passing inert fuel gases containing much carbon-dioxide into heat-exchanging direct contact with the other portion, raising the heat 30 of the then resulting gaseous products of the first mentioned portion, uniting therewith gaseous products from the other portion, and burning the united products, and abstracting 35 the heat generated by the burning.

6. The process of treating fresh incandescent coke to recover the heat values thereof, which comprises dividing the supply of coke into two portions, passing fuel gases of 40 different low degrees of thermal value and carrying different amounts of carbon-dioxide into direct heat-exchanging contact with said coke portions, uniting the then resulting gaseous products, adding air to such united 45 products, burning the resulting mixture, and passing the products of combustion in heat-exchanging contact with the air, and with portions of the fuel gases and of the said gaseous products.

50 7. The process of treating fresh incandescent coke to recover the heat values thereof, which comprises dividing the supply of coke into two portions, circulating fuel gases of comparatively low thermal value and containing carbon-dioxide in direct heat 55 exchanging contact with one of said portions, thereby producing carbonaceous fuel gases of higher thermal value, passing lean carbonaceous gases of low thermal value different 60 from the first-mentioned fuel gases into direct heat-exchanging contact with the other portion of coke, thereby raising the thermal value and the carbonaceous contents of the lean gases, thereupon additionally 65 heating said resulting lean gases, adding air

thereto, passing the resulting gas-and-air mixture over material capable of coking and burning the gas-and-air mixture in direct heat-exchanging relation therewith, thereby abstracting heat from said gas-and-air mixture, and uniting the resulting gases of combustion with the fuel gases first mentioned. 70

8. The process of treating fresh incandescent coke and recovering the heat values thereof which comprises causing a supply of 75 said incandescent coke to act directly upon carbonaceous lean fuel gases of lower temperature than the coke, thereby cooling said supply, mixing the then resulting gases with air, burning the gas-and-air mixture in heat exchanging relation with coke-forming carbonaceous material, thereby producing gases of combustion and coke, passing said gases of combustion in heat-exchanging relation with fresh supplies of lean fuel gases intermediate the coke-cooling stage and the coke-producing stage, treating another supply of glowing fresh coke with carbonaceous fuel gases of lower temperature, uniting the then resulting gases with a portion of the 80 gases of combustion referred to and abstracting the heat from the gas mixture. 85

9. The process of treating freshly prepared incandescent coke and recovering the 90 heat values thereof, which comprises acting 25 with a supply of fresh hot coke upon carbonaceous fuel gases of lower thermal value than said coke, thereby cooling said coke and heating the gases, additionally heating the resulting fuel gases, mixing heated air with said resulting heated fuel gases, burning said resulting gas-air-mixture in indirect heat-exchanging relation with carbonaceous, coke-forming material, thereby producing hot, incandescent coke and gases of combustion, causing part of said gases of combustion to flow in heat exchanging relation with air, and causing another portion of said gases of combustion to flow in heat-exchanging relation with a fresh supply of carbonaceous fuel-gases intermediate the coke-cooling stage and the coke-forming stage, and then abstracting the remaining heat of said last-mentioned portion of gases of combustion. 100 105 110

10. The process of treating freshly prepared highly heated coke and recovering the 115 heat values thereof, which comprises causing a supply of said hot coke to act in direct heat exchanging contact upon inferior fuel gases of lower thermal value than said coke, thereby cooling said coke and producing enriched and heated carbonaceous fuel gases, acting with another separate portion of said hot coke upon lean carbonaceous gases of lower thermal value than said last-mentioned coke portion, mixing the thereby enriched lean gases with hot air, burning the gas-and-air mixture in heat exchanging relation with cokable material, thereby producing highly heated 120 125 130

coke from said material and gases of combustion, passing a portion of said gases of combustion in heat exchange relation with air of combustion, and other portions of the
5 gases of combustion in heat exchanging relation with the said enriched lean gases and then uniting said last mentioned portion of gases of combustion and a supply of steam with said carbonaceous heated fuel gases,
10 and abstracting the heat of the resulting gas mixture by contact with heat consuming means.
